COIL-WINDING APPARATUS

George Stevens, Chicago, Ill.

Application June 11, 1946, Serial No. 675,995

2 Claims. (Cl. 242—25)

1

This invention relates to coil-winding machines and the like and is concerned primarily with the winding of a coil of generally cylindrical formation and made up of a series of overlapping sections in each of which the turns of the coil are reversed with the complete coil having ends that are conically shaded and arranged substantially parallel to one another.

One object, among others, is the provision of a machine embodying universal coil-winding mechanism and progressive coil-winding mechanism, operable together, i. e., at the same time.

Another object, among others, is the provision of improvements in both universal and progressive coil-winding mechanism.

Still another object is the provision of a ball bearing for the mandrel in said mechanism.

Another object has been the provision of improvements relating to the rack for operating the progressive stroke of the mandrel.

Another object is the provision of adjusting means for adjusting the stroke of the rack, said means including a stop clamp.

Still another object has been the provision of the foregoing in a manner which is relatively inexpensive, and simple to make, assemble and operate.

These and other objects and advantages will appear and be brought out more fully in the following specification, reference being had to the accompanying drawings, in which:

Fig. 1 is a top plan view of the winder.

Fig. 2 is a front elevation of the same, with the face plate removed.

Fig. 3 is a detail sectional view of the gear housing on the line 3—3 of Fig. 2.

Fig. 4 is an elevational view of the gear housing, with the back cover removed.

Fig. 5 is a detail sectional view of the gear housing, taken on the line 5—5 of Fig. 1.

Fig. 6 is a detail sectional view of the gear housing, taken on the line 6—6 of Fig. 3.

Fig. 7 is a plan view of the machine arranged for universal winding.

Fig. 8 is a plan view of the machine arranged for universal winding.

Fig. 9 is a side elevation of the supply spool, feeding rollers and brake drum.

In accordance with the present invention, a coil of substantially cylindrical formation is wound. The coil itself is made up of a series of overlapping sections in each of which the turns of the coil are reversed with the ends of the coils taking the form of substantially parallel cones. To accomplish this, the core of the coil is moved progres-

2

sively in one direction during the winding operation but the wire feeding means is reciprocated.

For the purpose of illustrating the principle of my invention, I have shown a flywheel pulley 10, mounted on a shaft 11, in walls 12 and 13.

The shaft 11 supports a chuck 14 at one end, and is provided with a driving thread 15, which is adapted to drive a gear 16, having bearing on the shaft 16a. Thereby, the shaft 11 drives a train of gears and operates a rack 18 back and forth.

The train of gears 17 includes a primary gear 17a on shaft 16a, and the train also includes intermediate gears 58 and 59, on studs 56 and 57, on gear support 50, to operate gear 17b, on shaft 40, to operate the rack 18, through the rack pinion 17c. Rotation of the pinion 17c moves the rack 18 toward the right, as viewed in Figures 1 and 2, during its working stroke, carrying with it the chuck 14 through the bracket 14, guide 75 and key 76. The reverse reciprocation of the rack 18 is manually effected as hereinafter pointed out.

Shaft 11 also has a spiral gear 73 adapted to operate a gear 19 on shaft 19a, which drives a train of gears.

The train of gears includes a primary gear 20, on shaft 19a, an intermediate gear 21 on pin 54, and gear 21a in front of gear 21, also on pin 54, looking at the cam side of the machine, as shown in Fig. 6.

The train also includes cam gear 22 on cam shaft 22a, to operate cam 23, the cam 23 being adapted to reciprocate the rod 26 as hereinafter pointed out. Guide members 24 and 25 are secured to the rod 26, and reciprocate therewith, the guide members being provided with guide rollers 24a and 25a over which the wire strands to be wound are trained.

Also fastened to the rod, are thimbles 27 and cone spacers 28, which are employed for the purpose of placing the guide members 24 and 25 in proper position with reference to the rod 26, dependent upon the kind and size of the coil to be wound.

One end of the rod is slidably supported in a suitable bearing carried by a standard 29, which also has bearing means which slidably supports the rack 18, the standard 29 being mounted on a base 30.

The chuck 14 supports a coil core on a mandrel 32, supported in bearing 33 in tail stock 34. The bearing 33 is slidably mounted on the bar 37.

Mandrel-removing means are provided, which include a handle 35, pivoted at 36 and connected to bar 37 at 38.

When the handle is swung to the right, looking at Fig. 1, the bearing is pulled against the spring 39, to allow the mandrel to be removed.

Attached to the rack-driving shaft 40 is a crank handle 41, for manual adjustment of the rack 18, and return of same when the limit of travel has been reached.

The cam 23 operates the rod 26, through a yoke 42 to which the rod is fastened, mounted upon the sliding rod 43, which, in turn, is mounted in bearings 44 and 45, in walls 12 and 13.

The cam 23 reciprocates the rod 26, and the short supporting rod 47 has a spring 48 to take up the slack. Reciprocation of the rod 26, and of the guides 24 and 25 and rollers 24a and 25a, carried by the rod 26, results in the wire strands connected to the core, carried by the mandrel 32, and drawn from the supply spools, being wound upon the core in convolutions inclined first in one direction, and then in a reversed direction, thereby effecting the so-called universal winding heretofore referred to. During reciprocation of the rod 26, the mandrel 32, carrying the core, is adapted to be advanced or progressed longitudinally with respect to the rod 26, through movement of the rack 18. The rack 18 carries the chuck 14 and mandrel 32 with it by reason of engagement of means on the rack 18, hereafter mentioned, with the chuck 14.

It will be understood that for different coils, different ratios of gears are required, and gear-changing means are provided.

In Fig. 2, I have shown the gear support 49, and in Fig. 4, I have shown the gear support 50.

There are also provided slots 51 for bolts and nuts 52, to secure the gear support 49 to the rack support 53.

At the other end, gear support 49 has a pin 54 extending through gear 21 and 21a.

The gear support 50, mounted on the base 55 of wall 63, has a pair of pins 56 and 57 extending through intermediate gears 58 and 59, in train 17.

For counting turns, a spindle 60 has a gear 61, driven by gear 73.

The spindle is shown located in bearings 62, fastened in removable rear wall 63.

The spindle may be connected to suitable counting mechanism, as shown, for counting the number of turns, etc.

The gearing is enclosed in walls forming a head 64.

The head 64 includes removable front wall 65, wall 63, wall 66 and integral upper walls 67, lower wall 68, and middle wall 69.

The front wall 65 is held in place by studs and thumb screws 70, or other suitable means.

The rear wall 63 is shown held in place by screws 71, and the rear wall 66 is shown held in place by stud screws and thumb nuts 72.

The shaft 11 is splined to a shaft 11a, on which the chuck 14 is mounted.

The shaft 11a has a ball-bearing connection with a bracket 74, which is secured to a guide 75 for the rack 18.

The guide 75 has mounted therein a key 76, which extends into a groove 77 in the chuck 14, to limit the lengthwise movement of the chuck, but not to interfere with the rotating movement of the chuck.

Also provided on the rack 18 is a limiting stop 78, consisting of a pair of brackets 79, which are apertured, as at 80, and bolted together by bolts 81.

Spool-holding means (Figure 9) include a

bracket 82, an intermediate bracket 83, a spindle holder 84, a spindle 85 and a circular guide plate 86.

There are also included braking means, including springs 87 and wood brake 88.

Secured to the spindle holder, is a roller support 89, over which the wire may be led to one of the rollers 24a and 25a.

One or more spindle holders for additional supply spools and rollers may be provided.

As will be manifest to those skilled in the art, both a universal and progressive winding are combined in the aforesaid machine. In the simplest mode of applicant's invention a single coil is wound on a single core.

When it is desired to wind a coil, a core for the coil is placed upon the mandrel 32. The mandrel 32 may readily be detached for this purpose by pressing back the resiliently held bearing 33, and removing the mandrel from the chuck 14. Once the core is in position on the mandrel 32, the latter is replaced in the chuck 14 and bearing 33, and upon rotation of the chuck 14, the mandrel 32 will be rotated, which will rotate the core. The guide members 24 and 25, carrying the guide rollers 24a and 25a respectively, are adapted to be reciprocated by the rod 26, adjustment and positioning thereof being effected by employment of the thimbles 27 and spacers 28 heretofore mentioned. The rack 18 may be moved in a left-hand direction as viewed in Figure 1, to any selected position at which it is desired to start the winding, through manipulation of the handle 41, to rotate the gear 40 in a direction the reverse of that in which it is normally driven by the power means.

With the wire strand or strands from the spool or spools 86 trained over the guide rollers 24a and 25a, and secured to the core on the mandrel 32, the power is turned on. Through gears 16, 16a, 17a, 17b and 17c, slow forward motion toward the right is imparted to the rack 18. The rack 18 through the bracket 75, picks up the chuck 14, and the parts associated therewith, and carries them slowly forward, these parts being rotated by the spline shaft 11a, which also permits the forward movement of the chuck 14. During this movement the wire strands are wound progressively along the rotating core carried by the mandrel 32, the strands being pulled from the spools 86 over the guide rollers 24a and 25a and about the core. Simultaneously with the movements described, through the shaft 11, gears 19, 20, 21 and 22, the cam 23 is rotated, and through the yoke 42 transmits reciprocating motion to the rod 26. This in turn imparts like motion to the guide rollers 24a and 25a, so that as the mandrel 32 is traveling longitudinally forward, the guide rollers 24a and 25a move back and forth, and cause winding of the wire to incline in one direction with respect to the rotating core, and then in a reverse direction, the number of reciprocations of the guide means during the longitudinal travel of the core, controlling the number of reversals of the winding on the core. Thus both universal and progressive winding of the wire upon the core are carried out simultaneously. At the end of the run for one coil, the parts are replaced for the next run by rotating the handle 41, which through the rack 18 restores the chuck 14 and other parts to their initial position. As already pointed out the idler gears 58 and 59, or cam driven gear 21a may be adjusted to cut out one or the other

of the two operations so that they may be employed independently.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variation and modifications as come within the scope of the appended claims.

Having thus described my invention, what I claim as new and desire to secure by Letters Patent is:

1. In a device of the kind described, means for winding a coil progressively, said means including a rack; a stop for limiting the travel of said rack; and a handle for returning said rack, after it has reached its limit of travel, to its original position.

2. Apparatus of the character described, comprising: a rotatable member upon which a strand is to be wound; means for rotating said member, including a splined shaft and a chuck carried by said shaft for supporting said member; a rack; means for advancing said rack; means

operatively connecting said rack with said chuck to effect advance of said member; a reciprocatory element; and means carried by said element for guiding said strand back and forth along said member during advancement thereof by said rack.

GEORGE STEVENS.
